UNITED STATES PATENT OFFICE.

EDWARD G. THOMAS, OF SPRINGFIELD, ILLINOIS.

SYNCHROROTOR.

1,381,367.

Specification of Letters Patent. Patented June 14, 1921.

Application filed June 12, 1916, Serial No. 103,208. Renewed August 28, 1918. Serial No. 251,837.

To all whom it may concern:

Be it known that I, EDWARD G. THOMAS, of Springfield, county of Sangamon, State of Illinois, have invented and produced certain new and useful Improvements in Synchrorotors, of which the following is a specification, reference being had to the accompanying drawings, which form a part thereof.

10 My invention is intended to provide an improved apparatus by which the movements of a mechanical device, such as a rotating shaft may be controlled by and made synchronous with the periodic movements 15 of another device, for example, a pendulum or another rotating shaft. For convenience the former device and its operating mechanism may be termed the "governed device," and the latter the "controlling device." This 20 invention is an improvement on the invention disclosed and claimed in applicant's U. S. Patent #1045909 and may be applied to similar uses.

The controlling device may consist of 25 any assemblage of parts having a periodic rotary or reciprocating motion, such as a clock pendulum, while the governed device may be described in a general way as comprising—

30 A rotating member which is driven by power from an outside source, a device for adjusting the speed of the driving mechanism so that it shall tend to drive the rotating member at a speed slightly below the 35 desired rate or at a speed slightly above this rate, means for selecting one speed or the other of the driving mechanism in accordance with the angular position of the rotating member at the time of such selection.

40 and apparatus connected with the controlling device for causing such a selection to periodically occur. If the rotating member shall have turned through a less arc than is represented by its desired rate of rotation, 45 the greater speed of the driving mechanism will be selected, while if the rotating member shall have traveled through a greater arc than is desired, the slower speed will be chosen for the driving mechanism during 50 the next period. Thus the rotating member will alternately be accelerated and retarded in order that its total revolutions shall correspond exactly to those represented by the

desired rate except for the minute differences which will occur between the periodic 55 selections.

While the apparatus may be made to accomplish the results desired by the use of mechanical parts, electricity can be used to advantage in simplifying the construction of 60 the mechanism and the specific form to which the greater part of the following description applies is that in which the controlling and governed devices are electrically connected.

65 Figure 1 is a plan view partly in section of a preferred form of the mechanism employed as a governed device, and also showing a pendulum clock used as a controlling device. Fig. 2 is a side view of the fly wheel 70 of the governed device and contact brushes. Fig. 3 is a side view of the balance wheel showing the speed regulating mechanism. Fig. 4 is a side view of the balance wheel showing a modified form of the speed regulating mechanism.

75 Referring to Figs. 1, 2, and 3 the controlling device consists of a clock 1 arranged to momentarily close an electric circuit at each swing of its pendulum 2. At the lower end 80 of the clock case is located a block 3 having a recess in its upper surface containing a little mercury 4 of such volume that the meniscus formed by its upper surface will project above block 3 and into the path 85 of pendulum 2 as it swings to and fro, so that the lower end of the pendulum touches the mercury, at every swing, thereby momentarily closing an electric circuit, of which one wire is electrically connected to the pendulum 2 and the other touches the mercury 4.

90 This circuit controller is entirely diagrammatical in character, is not a part of this invention, and may be replaced by any other form of mechanism which will serve to 95 periodically open and close an electric circuit.

95 The governed device comprises, according to the construction shown, an electric motor 11 having an extended shaft 12 suitably journaled in a support 13 secured to the 100 base of the machine 14 and having firmly secured to it a balance wheel 15. Upon the shaft 12 a fly wheel 100 is rotatively mounted and one end of a torsion spring 16 encircling the shaft is fastened to the fly 105 wheel. The other end of spring 16 is fas-

tened to a collar 16' tightly secured to shaft 12 by a set screw, the spring thus forming an elastic driving connection between shaft 12 and fly wheel 100. To the fly wheel 100 is 5 secured in any suitable manner the mechanism to be synchronized herein diagrammatically represented by bevel gear 17, bevel gears 18 and 19, rotatively mounted in gear 21, bevel gear 20 and commutator 22 rigidly 10 secured together and rotatively mounted on shaft 12. Gear 21 is also mounted on shaft 12 so as to be able to turn freely thereon. Bevel gears 17, 18, 19, and 20 and their 15 mounting gear 21 constitute a differential gear of which the purpose will be disclosed later.

Two speed regulating devices 23 and 24 are mounted on balance wheel 15. Device 23 consists of a weight 25 pivoted at 26, and 20 having a relatively long arm 27 extending inwardly and adapted to move between a stop 29 and a contact screw 30 tapped into an insulating block 31. A tension spring 32 tends to hold the arm 27 against stop 29 25 and to resist any tendency of the arm to move toward the contact screw caused by the centrifugal force of the weight 25 when the apparatus is in motion. Below the speed at which the device is set the force of the 30 spring will overcome the centrifugal force of the weight and hold the arm away from the contact screw 30, while above this speed the centrifugal force of the weight will preponderate and cause the arm to make contact with screw 30.

Speed regulating device 24 is similarly constructed of weight 25' pivoted at 26', arm 27', stop 29', contact screw 30' mounted in insulating block 31' and spring 32'.

40 Contact screw 30 is connected by a wire 33 with a contact ring 34 mounted on an insulating ring 35 on shaft 12, and contact screw 30' is connected with contact ring 34' on insulating ring 35, by a wire 33'. Contact brushes 75 and 75' are mounted on an insulating block so as to register with and touch the contact rings 34 and 34'.

The motor 11 is direct current, shunt wound and receives current from any extraneous source by means of the wires marked "Line". The field and armature of the motor are in multiple. In the field circuit is placed a resistance 40, which may be short-circuited by the closing of a relay switch 41, which will allow the field current to pass around the resistance 40, through wires 42 and 43. Since the speed of the motor may be varied by varying the strength of its field, the motor will run faster when the 55 relay is open than when it is closed, since the resistance of the field circuit will be greater when the resistance 40 is in circuit than when it is cut out by the closing of the relay. The motor and resistance should be 60 so designed and related that the motor will 65

run at a speed somewhat under the lowest speed at which either of the speed regulating devices is set to act, when its field circuit is shunted around resistance 40; and at a speed somewhat higher than the highest 70 speed at which either of the speed regulating devices is set to act, when resistance 40 is in the motor field circuit. A five per cent. difference between the low speed of the motor and its high speed is considered 75 a desirable amount.

The motor speed will not, however, reach these extremes since the governor arm 27 will make contact with contact point 30 before the motor can reach the speed at which it would run were resistance 40 permanently placed in the motor field circuit, thereby making the motor slow down by causing resistance 40 to be cut out of the motor field circuit by relay 41; and the governor arm 27 will break contact with point 30 before the motor can reach the speed at which it would run were resistance 40 permanently cut out of the motor field circuit, thereby making the motor speed up by causing the relay 41 to insert the resistance 40 in the motor field circuit. When under the control of one of the speed regulating devices the variation of motor speed from the speed at which the speed regulating device is set to act should be very little and will depend on the delicacy of the apparatus.

It will be obvious that the motor is not governed in reference to the desired uniform speed of the synchrorotor as a whole but in reference to the speed at which the particular speed regulating device in use at the moment is set. The two speeds corresponding to the two speed regulating devices are the only speeds at which the motor will tend to run and neither of these speeds is that of the synchrorotor as a whole. One is greater and the other is less.

The circuit operating relay 41 includes wires 44 from the coil of the relay, battery 45, wire 46 to a ground 47 on the base 14, thence to fly wheel 15, to the speed governing device 23 or 24, wire 33 or 33', contact ring 34 or 34', to contact brush 75 or 75', wire 77 or 77', to the contact point 76 or 76' of a double relay 48, thence to relay lever 49, and through wire 50 to the coil of relay 41. It will be seen that according to the position of relay lever 49 against one contact point 76 or 76', speed regulating device 23 or device 24 will be in the circuit of relay 41 and will regulate motor 11 to run close to the particular speed for which the speed regulating device is designed, by opening or closing the relay circuit as the balance wheel varies in speed, putting resistance in the motor field when a higher speed is needed and cutting it out when a lower speed is desired, to the end that the average motor speed shall ap- 130

proximate closely the speed at which the speed regulating device is set to act.

The purpose of the double relay 48 is to switch into circuit the particular speed regulating device 23 or 24 made necessary by the angular position of fly wheel 100 at the moment that the circuit is closed by the pendulum 2 touching mercury bubble 4 and in order that double relay 48 shall make the proper selection a contact block 78 is mounted on the periphery of the fly wheel 100 in such a position as to make contact in each rotation with two brushes 51 and 52 mounted on an insulating block 79 attached to the base of the machine. The contact points of brushes 51 and 52 are not side by side, but are located in such angular relation to the fly wheel that one brush 52, will be just passing from contact with block 78 as the other brush 51, makes contact with it. Brushes 51 and 52 are connected by wires 53' and 53 to coils 54' and 54 of relay 48 and the circuit continues through common wire 55 to the clock operated circuit breaker shown diagrammatically by the mercury bubble 4 in the path of pendulum 2 and thence through wire 59 to the battery 45 and wire 46 to the base 14.

The operation of the mechanism illustrated is as follows: We will assume that the clock movement selected is one beating seconds and therefore adapted to close and open the circuit of the double relay 60 times per minute and that the speed desired for the governed mechanism is 60 revolutions per minute. It is then assumed that speed regulating mechanism 23 be carefully adjusted to act at a speed of 61 revolutions per minute and speed regulating device 24 be set at 59 revolutions. The apparatus may then be started up and will be brought to a speed of 61 revolutions if the lever of the double relay happens to be in contact with contact 76 or 59 revolutions if touching with 76'. The apparatus will then in a few revolutions reach a position such that one of the contact brushes 51 or 52 will be in contact with contact block 78 at the moment when the circuit of the double relay is closed by the clock-operated circuit breaker.

We will assume that the mechanism is running at 61 revolutions per minute. Then contact block 78 will come into contact first with brush 52 at the moment when the clock operated circuit breaker makes contact. As lever 49 is already in contact with contact point 76, which is connected with the fast speed regulating mechanism, no change will result and the synchronotor will continue to run at 61 revolutions and will gain in angular motion till contact block 78 is no longer in contact with brush 52 but is in contact with brush 51 at the moment when the circuit is closed by the clock operated circuit

breaker. When this occurs coil 54' of the double relay 48 will be momentarily energized and relay lever 49 will be attracted and will be pulled against contact point 76'. The slower governor 24 will now be in circuit with the relay 41 and the speed of the motor will accordingly be reduced rapidly to 59 revolutions. The fly wheel will at first have the higher rotative speed corresponding to the faster governor, but will be retarded by the slower motion of the motor, though a part of the difference in speed will be absorbed temporarily by the spring 16 since the inertia of fly wheel 100 will have to be overcome. If the reduction of the angular motion of fly wheel 100 during the period before the circuit of relay 48 is again closed by the clock is so great that contact block 78 is in contact with brush 52 when the clock closes the circuit, coil 54 of relay 48 will be energized and will pull lever 49 from contact point 76' to contact point 76 and thus switch the circuit of speed governing relay 41 to the faster speed regulating mechanism 24. Then during the next period of one second the motor will run at 61 revolutions and the fly wheel will be accelerated. If, however, the reduction in the angular motion of fly wheel 100 is not great enough to bring contact block 78 under brush 52 at the moment of the closing of the double relay circuit by the clock, but instead brush 51 is in contact, relay coil 54' will be energized and will retain lever 49 against contact point 76'. The motor will then continue to run at 59 revolutions and the fly wheel 100 still further retarded. An ideal condition will be reached when the speed regulating devices are alternately in circuit in succeeding periods. In any event the inertia of the motor, the elasticity of the spring 16, and the inertia of the fly wheel 100, all will tend to reduce the actual acceleration or retardation of the fly wheel, which will occupy within close limits a median position in reference to brushes 51 and 52 at the moment of the closing of the circuit by the clock-operated circuit breaker.

By a suitable relation between the inertia of the fly wheel and synchronized mechanism and the strength of the driving spring, the variation in speed of the mechanism during a given period may be made so small as to be negligible. The synchronized fly wheel 100 and attached gears and commutator will therefore be given a substantially uniform speed of rotation at a rate bearing a definite relation to the periodicity of the circuit breaker at the controlling device.

The speed of the apparatus may be any multiple or integral part of the rate of the periodic circuit breaker if the apparatus is so designed, for even if contact block 78 makes contact with brushes 51 and 52 sev-

eral times during a period no action of the selecting relay will take place except at the moment when the circuit is closed at the clock. Since a motor of slow speed is large and costly it will be desirable to drive shaft 12 from motor 11 by gearing so that the motor may run at a suitable high speed.

In Fig. 4 there is shown the use of a single speed regulating device having two contact points to replace the pair of speed regulating devices shown in Figs. 1 and 2. This form of the apparatus consists of a weight 25 pivoted at 26, arm 27, stop 29, contact screw 30 mounted in insulating block 31 and spring 32 similar to the parts of the mechanism previously described. A contact spring 90 mounted on an insulating block 91 carries a contact point 92 interposed between arm 27 and contact screw 30. Wire 33 leads from contact spring 90 to contact ring 34 and wire 33' from contact screw 30 to contact ring 34'. When the apparatus is at rest contact point 92 is normally not in contact either with arm 27 or screw 30. When the apparatus is started up and reaches a speed at which the centrifugal force of weight 25 will overcome the force of spring 32 arm 27 will move toward and make contact with contact point 92 and if the slower speed has been chosen by the selecting mechanism so that contact point 92 is in the circuit of relay 41, the motor speed will at once be checked until the speed of the balance wheel is reduced to point where spring 32 can overcome centrifugal force of weight 25 and move arm 27 out of contact with contact point 92, thereby opening circuit 41 and reducing the speed of the motor. If however, the selecting apparatus has chosen the higher speed, contact point 92 will not be in circuit but contact screw 30 will be. The centrifugal force of weight 25 will now have to overcome the resistance of spring 32 as before but also will have to bend spring 90 sufficiently to allow contact point 92 to touch screw 30. This extra work will require the apparatus to run at a higher speed than before to produce the necessary centrifugal force, and the motor will be governed accordingly.

An important use of my device is in connection with the production of musical sounds in that class of instruments, such as the choralecello, wherein steel strings, supported, in connection with a sounding board, upon a piano plate, are vibrated by the action of electromagnets, placed in juxtaposition thereto and periodically energized by an interrupted current. In Fig. 1, a piano plate 80, carries a steel string 81, and the sounding board 82. String 81 bears at one end on a bridge 83, secured to sounding board 82, and upon a rail 84 at the other, and is stretched between pin 85 and tuning pin 86 in the usual manner. Mounted on a

bracket 87 and opposite the string, but not in contact therewith, is a magnet 88. The circuit 89 of this magnet includes contact brush 69, commutator 22, the frame of the machine, a source of electric current 71 and a circuit breaker 90 operated by a piano key 91. The commutator 22 in this case consists of nearly equal segments of conducting and insulating materials, all the conducting segments being electrically joined to one another and to the frame of the machine. Now when the key 91 is pressed down and closes circuit breaker 90, a rapidly interrupted current is sent through the magnet 88, which periodically attracts and releases the string 81. If the periodicity of the interrupted current is the same as the rate of vibration of the string, it is thrown into vibrations sufficient for producing strong musical tones. As it is found that an extremely small difference between the periodicity of the current and the rate of vibration of the string is sufficient not only to destroy the desired quality of the tone produced, but also to very greatly diminish the volume, it is essential that the speed of the commutator 22 shall be uniform and definite.

A shaft 60 suitably supported in bearings 61 and 62 secured to base 14 carries a pinion 63 which meshes with gear 21. Shaft 60 is splined and slidably mounted thereon is a friction wheel 64 which is keyed to shaft 60 so that wheel and shaft will rotate together. Wheel 64 is engaged by fork 65 attached to an adjusting rod 66 by means of which friction wheel 64 may be moved to any position along shaft 60. Friction wheel 64 touches and may be driven by a cone 67 rotatably mounted and arranged to be driven from any convenient source of power through a belt pulley 68. Cone 67 is in driving contact with wheel 64 in all positions of the latter along shaft 60 and obviously will impart to it and through it to gear 21 of the differential a speed of rotation varying in accordance to the position of wheel 64. Every complete rotation of gear 21 will cause two rotations of bevel gear 20 and commutator 22 and if such rotation is accomplished while the synchrorotor is in operation, the rotation of the commutator resulting will be added to or subtracted from the rotations caused by the synchrorotor according to the relative direction of the respective motions.

The differential gear and the means for driving will also serve for changing the angular position of the commutator 22 where it is not desired to continuously add to or subtract from its rotations. This will be effected by turning shaft 60 by hand to the extent desired.

The circuit established through commutator 22 and contact brush 69 may be used

for any signaling purpose, such as telegraphy. Any or all of the bars of the commutator 22 may be grounded on shaft 12 and such bars, shaft and the frame of the machine made parts of the signaling circuit. Other brushes contacting with commutator 22 may be added if other signaling circuits are desired. As an illustration we may assume that all the commutator bars except one are completely insulated and that the remaining bar is grounded on shaft 12. Obviously once in each revolution of the commutator the circuit will be completed through the grounded commutator bar and brush 69 and an impulse sent into the line. If more than one impulse per revolution is desired it is only necessary to connect other bars with the first.

The adjustment of the actual rotational speed afforded by the differential gear and the variable speed drive will be most desirable in synchronous telegraphy where it is desirable to keep in step commutators or kindred devices at distant points in order to accurately distribute among a number of local circuits at one point, the impulses sent from a similar number of local circuits at another point and transmitted over a single line or by the methods of wireless telegraphy between the two points, as is done in the systems of Delaney, Rowland, and others. We will assume that synchrorotors are located at these points and that the controlling devices are clocks having pendulums beating seconds and operating circuit breakers once per second. Even with the most accurate clock mechanism exact isochronism cannot be attained and a difference between the clocks of from one to five beats per day may be expected. As the number of beats of a seconds pendulum per day is 86,400 it will obviously be necessary at one point to add to or subtract from every 86,400 rotations of the synchrorotor a number of rotations equal to the difference between the beats of the two clocks per day. This will be accomplished and made synchronous by a suitable arrangement of the differential gear and variable speed drive.

My device may be modified in many structural respects, and by the substitution of mechanical or electrical equivalents for any of the parts of the mechanism without thereby necessarily altering its essential operation. Such modification will readily occur to those skilled in mechanic arts and I have not deemed it necessary to illustrate them here.

I claim as my invention the following:

1. In a synchrorotor the combination of a rotatively supported member, a spring of which one end is fastened to said member, and means for causing rotation of the other end of said spring at one or the other of two predetermined speeds, and mechanism for

periodically selecting one or the other speed of rotation.

2. In a synchronizing apparatus the combination of a governed device including a rotating member, a power driven shaft, and speed governing apparatus adapted to cause said shaft to revolve at one or the other of two predetermined speeds, with mechanism for periodically selecting one or the other of said two speeds for the rate at which said shaft shall revolve.

3. In a synchronizing apparatus, the combination of a governed device, comprising a rotating member, driving means therefor, and speed governing apparatus adapted to cause said driving means to run at one or the other of two predetermined speeds, with mechanism for selecting one or the other speed, and a controlling device adapted to periodically cause said mechanism to act.

4. In a synchronizing apparatus a governed device comprising a rotating member, driving means therefor, two speed governing devices arranged to control said driving means and means for selecting one or the other device to control said driving means in combination with mechanism adapted to periodically cause said means to act.

5. In a synchronizing apparatus a governed device, comprising a rotating member, driving means therefor, speed regulating apparatus arranged to govern said driving means at two predetermined speeds and an electrically controlled means for periodically adjusting said apparatus to one or the other of said speeds.

6. In a synchronizing apparatus the combination of a governed device comprising a revolving member, apparatus to be synchronized connected therewith, driving means, speed regulating apparatus arranged to govern said means at either of two predetermined speeds, and means adapted to adjust said apparatus to one or the other of said speeds, with a controlling device for periodically causing said means to act.

7. In a synchronizing apparatus the combination of a governed device comprising a revolving member, driving means therefor, and speed regulating apparatus arranged to govern said driving means at two predetermined speeds, with time controlled means for adjusting said apparatus to one or the other of said speeds in accordance with the angular position of said revolving member and a controlling device for periodically causing said means to act.

8. In a synchronizing apparatus the combination of a governed device comprising a revolving member, driving means therefor, an elastic connection between said revolving member and said driving means, and speed regulating apparatus adapted to control said driving means at either one of two predetermined speeds, with a device for select-

ing one of the two speeds, and a controlling device for causing said selection to take place.

9. In a synchronizing apparatus the combination of a governed device comprising a revolving member, driving means therefor, speed regulating apparatus adapted to cause said driving means to run at one or the other of two predetermined speeds, and 10 an electrically controlled means for causing a selection to be made between said two speeds and a clock-operated circuit breaker in the circuit of said electrically-controlled means.
- 15 10. In a synchronizing apparatus the combination of a governed device, comprising a revolving member, driving means therefor, consisting of an electric motor, and speed regulating apparatus adapted to cause said 20 motor to rotate at one of two predetermined speeds, said apparatus including means for varying the resistance of a part of the motor circuit, with means for causing a selection of one of said two speeds to be made, and a 25 device for periodically causing said means to act.

11. In a synchronizing apparatus the combination of a governed device comprising a rotating member, driving means therefor, 30 and speed regulating apparatus adapted to cause said driving means to run at one of two predetermined speeds with an electrically operated speed selecting mechanism and a controlling device for periodically 35 opening and closing the circuit of said mechanism.

12. In a synchronizing apparatus the combination of a governed device comprising a rotating member, driving means therefor, 40 an elastic connection between said member and said driving means, and speed regulating apparatus adapted to cause said driving means to run at one or the other of two predetermined speeds, with means for adjusting said apparatus to one or the other of said speeds in accordance with the angular position of said revolving member and clock-operated means for periodically causing said means to act.

- 50 13. In a synchronizing apparatus the combination of a governed device comprising a rotating member, a direct current electric motor having a shunt field winding, and a resistance in said shunt, and speed regulating 55 apparatus adapted to cause said motor to run at one of two predetermined speeds and arranged to operate by opening and closing a circuit around said resistance with means

adapted to select one of the two speeds in accordance with the angular position of 60 said revolving member at the time of selection and a controlling device for periodically causing said selecting means to act.

14. In a synchrorotor the combination of a governed device including a rotating member, having apparatus to be synchronized attached thereto, a driving shaft, an elastic connection between said shaft and said rotating member, and speed regulating apparatus adapted to cause said shaft to revolve 70 at one or the other of two predetermined speeds and selecting mechanism adapted to periodically determine at which speed said shaft shall revolve.

15. In a synchrorotor, the combination 75 with an electric circuit and means for producing periodic interruptions therein of a governed device comprising a rotating member, driving means therefor, speed regulating apparatus adapted to cause said driving 80 means to run at one or the other of two predetermined speeds, speed selecting means operated by said electric circuit, a mechanism to be synchronized, including two rotating parts and means for varying the relative 85 rotational speed of said parts.

16. In a synchronizing apparatus the combination of a governed device including a rotatively supported member consisting of 90 two parts, a spring of which one end is fastened to said member, means for rotating the other end of the spring at one or the other of two predetermined speeds and a variable speed mechanism for changing the relative speed of rotation of the parts of 95 said member, with speed selecting mechanism and means for periodically causing a selection to be made.

17. In a synchronizing apparatus the combination of a governed device containing a 100 rotating member, a contact sector attached thereto, driving means therefor, and speed governing apparatus adapted to cause said driving means to run at one or the other of two predetermined speeds, with mechanism 105 for selecting one or the other of said speeds including two contact members arranged to touch said contact sector at different angular positions of said rotating member.

In testimony whereof I have signed my 110 name to this specification in the presence of two subscribing witnesses.
